UNITED STATES PATENT OFFICE.

JOHN KENNY, OF AMHERST, NOVA SCOTIA, CANADA.

BROOM-PROTECTOR.

No. 876,884.

Specification of Letters Patent.

Patented Jan. 14, 1908.

Application filed October 24, 1906. Serial No. 340,423.

To all whom it may concern:

Be it known that I, JOHN KENNY, a subject of the King of Great Britain, residing at Amherst, in the Province of Nova Scotia and 5 Dominion of Canada, have invented new and useful Improvements in Broom-Protectors, of which the following is a specification.

This invention relates to an improvement in brooms, comprehending specifically a 10 broom constructed of waste products of wood working factories cut to the desired size and length.

In connection with a broom of this character the invention contemplates an adjustable 15 protector which is adapted for maintaining the broom head in shape under all conditions of wear and which may be adjusted longitudinally of the broom head to prolong the life of the broom and increase its effectiveness.

20 The invention will be described in the following specification, reference being had particularly to the accompanying drawings, in which:

Figure 1 is a view in elevation showing my 25 broom, Fig. 2 is a similar view, the protector being in open position, illustrating particularly the means for securing the protector in place, Fig. 3 is a plan of the protector, Fig. 4 is a section on line 4—4 of Fig. 1.

30 Referring particularly to the drawings my improved broom is in usual form having a head constructed of slivers of hard wood A which may be readily secured from the waste products of any wood working factory, and 35 are, of course, to be of a size and length necessary for the most effective result desired in connection with the particular broom.

As a means for securing the material of the head in position and providing for the adjustment necessary to compensate for the wear of 40 the broom, my invention also contemplates the use of a protector. This protector comprises a casing corresponding in sectional contour to the shape of the broom head 1 and 45 preferably divided longitudinally into duplicate members 2 and 3. The respective members are arranged for hinged connection through the medium of rings 4 passed through the members adjacent one edge of each, and 50 maintained in closed or operative relation through the medium of catches 5 carried by one member designed to engage appropriately formed lips 6 carried by the other member. Each member is formed at the 55 relatively upper end with a vertically projecting semi-cylindrical extension 7, said extensions

together forming, when the members are in closed relation, a sleeve designed to embrace the handle 8 of the broom. The sleeve is preferably of truncated cone shape, the wall 60 thereof inclining inwardly from the connection with the protector toward the upper or free end, each extension 7 being formed at the relatively upper end with a laterally or inwardly extending series of spur teeth 9, 65 designed when the members of the protector are arranged in closed relation to take into the wood of the handle and prevent independent endwise movement of the protector. A securing collar 10 is arranged for coöperation 70 with the sleeve extension, said collar being of annular form in cross section and designed to be passed over the free end of the broom handle. The wall of the collar is inclined to correspond with the inclination of the wall of 75 the sleeve, being furthermore of such diameter relative to the diameter of the sleeve as to cause the collar to engage the wall of the sleeve in operative position of the collar and force the teeth 9 into the material of the 80 handle. Each member of the protector is formed near the relatively lower or free end with a transversely disposed row of spur teeth 11, designed when the protector is in operative position to be forced into the material 85 of the broom head and further aid in securing the protector against independent movement.

In applying the protector to the broom the members thereof are separated, as indicated in Fig. 2, and one of the members applied in position to partially envelop the broom head and handle. The second member is folded upon the hinge connection 4 and secured to the applied member through the 90 medium of the catches 5. The collar 10 is passed over the upper end of the broom handle and forced down to embrace the extensions 7 of the respective members, such operation serving to force the teeth 9 of the extensions 100 into the material of the handle. The protector is preferably of somewhat less length than the length of the broom head, so that in the initial adjustment of the protector to a new or unused broom the protector 105 will accurately and snugly fit the broom head throughout. As the broom wears in use, however, the protector may be readily raised relative to the broom head to provide for the projection of a sufficient length of the broom 110 head beyond the lower edge of the protector.

From the construction described it will be

noted that the protector is adjustably secured relative to the broom through the medium of the teeth 9 and 11, and that said protector is adapted for ready and convenient 5 adjustment in any position longitudinally of the broom head. The construction, therefore, provides for the use of the protector with a broom until the head of the same, or the effective portion thereof, is entirely worn 10 away, it being noted in this connection that the relatively free or lower edge of the protector serves as a binding medium for the material of the broom head and thereby maintains said material in the close compact condition most effective in use.

The material of the broom proper is preferably of hard wood, which in conjunction with the protector described insures a most effective broom head. The adjustable protector insures the adjustment of the broom 20 head to provide for taking up the wear of the broom bristles and thereby materially prolonging the life of the broom. Furthermore, the protector avoids the necessity of the usual 25 broom sewing, as it acts as an effective binder for the broom brush. The invention also contemplates the finishing of the broom in

any or all colors desired so as to provide an ornamental and attractive article.

Having thus described the invention, what 30 is claimed as new, is:—

The combination of a broom comprising a head and a handle, with a protector comprising a two-part shell or casing having continuous unperforated walls and semi-frusto-conical handle-engaging portions, handle-gripping means on the said portions, rings 35 permanently and hingedly connecting the parts of the casing together at one side, spring catches for locking the parts of the 40 casing together around the head at the opposite side to form a closed and tight housing around the head, gripping means on the parts of the casing for engaging the head, and a hollow frusto-conical member frictionally 45 held on the said portions and co-operating with the latches to hold the parts in locked position.

In testimony whereof I affix my signature in presence of two witnesses.

JOHN KENNY.
